(57) **CLAIM**

The ornamental design for an arrowhead, as shown and described.

DESCRIPTION

FIG. 1 is a front perspective view of an arrowhead showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is a bottom perspective view thereof; and,

FIG. 9 is a side perspective view of the portion of FIG. 6 outlined by the dot-dash broken line.

The evenly spaced broken lines in the drawings depict portions of the arrowhead that form no part of the claimed design. The dot-dash broken lines in FIG. 6 depict the viewing angle of FIG. 9 that form no part of the claimed design.
